UNITED STATES PATENT OFFICE.

JOHN SCOTT TAYLOR, OF LOGANSPORT, INDIANA, ASSIGNOR OF ONE-FOURTH TO ENOS D. MORGAN AND ONE-HALF TO JOSEPH TAYLOR, CLARK M. TAYLOR, DAWES TAYLOR, AND ZACHARY TAYLOR, ALL OF LOGANSPORT, INDIANA.

AXLE-BOX.

No. 840,399.

Specification of Letters Patent.

Patented Jan. 1, 1907.

Application filed October 12, 1905. Serial No. 282,476.

To all whom it may concern:

Be it known that I, JOHN SCOTT TAYLOR, a citizen of the United States, residing at Logansport, in the county of Cass and State of Indiana, have invented certain new and useful Improvements in Axle-Boxes; and I do hereby declare the following to be a full, clear, and exact description of the invention, such as will enable others skilled in the art to 10 which it appertains to make and use the same.

My invention relates to carriage-axles and axle-boxes.

It has for its object to provide an improved 15 construction of axle and box which will be simple in construction, cheap of manufacture, and dustproof.

The invention consists in the features of construction and combinations of parts here- 20 inafter described, and particularly pointed out in the claims concluding this specification.

In the accompanying drawings, illustrating 25 the preferred embodiment of my invention, Figure 1 is a longitudinal section of the box or bearing, showing its application to an axle or spindle. Fig. 2 is an inner face view of the inner clamping plate or ring, and Fig. 3 is a cross-sectional view on the line x x of 30 Fig. 1.

Referring more particularly to the drawings, in carrying out my invention I provide the spindle 1 with a transverse groove or slot 2 about midway of its length, very much as 35 in my Patent No. 799,204, dated September 12, 1905. The inner end of said spindle is provided with a shoulder-ring or collar 3, as in my said patent; but said spindle is straight instead of tapered at its outer end.

40 The shoulder-bearing 4 is constructed the same as in my said patent, except that the inner edge of the restricted end portion 5, which fits within the shoulder-ring or collar 3, is cut away, as at 4^a, and packed with 45 packing 4^b, held in place by a fiber ring 4^c. The intermediate nut-surface 6 and threaded restricted portion 7 of said shoulder-bearing 4 are formed as shown, the latter being adapted to be engaged by the boxing 8, which is 50 screw-threaded for that purpose. The shoulder-bearing is held in place by the broad sleeve 9, fitting over the central portion of the

spindle and having a transverse perforation 10 therein registering with the groove 2, so that the tapered pin 11 (shown in Fig. 3) 55 may engage both and lock them together. At each end of said sleeve is inserted a fiber ring 12 to take up the end thrust.

At its inner end the boxing 8 has an outwardly-extending shoulder 13, against which 60 abuts the inner clamping ring or plate 14. Said plate is keyed, as at 15, to the boxing, and its inner face is serrated or corrugated at 16 to engage the spokes 17. Near its outer edge said clamping-plate is also provided 65 with perforations 18 for the passage of bolts 19, comprising additional means for securing the spokes. Another clamping ring or plate 20 is mounted over the outer end of the boxing and, like the inner one, is provided with 70 serrations 21 on its inner face and bolt-holes 22 near the edges and adapted to register with those in said inner ring. The outer end of said ring or plate 20 is of less interior diameter than the other portion thereof and is 75 adapted to fit over and abut against a shoulder 8^a on said boxing. Said outer clamping-ring is secured in place, where it will clamp the spokes by the nut 23, screwed on the end of the boxing. 80

It will be noted that the packing between the shoulder-bearing and the spindle prevents the oil from escaping. The exterior diameter of the sleeve 9 is somewhat less than the interior diameter of the boxing to 85 provide a chamber for oil. The serrations on the faces of the clamping-rings grasp the spokes firmly and aid in securing said spokes in place.

Having thus described my invention, what 90 I claim as new, and desire to secure by Letters Patent, is—

1. The combination, with a spindle having a shoulder-ring at its inner end, of a boxing, a shoulder-bearing fitting around said spindle and having a portion for engagement with the boxing and a portion fitting within said shoulder-ring, means to retain the shoulder-bearing in place, the inner edge of the portion of said shoulder-bearing which extends within the shoulder-ring being cut away, and packing arranged within said shoulder-ring around the spindle in the recess formed by cutting away said edge. 95 100

2. The combination, with a spindle having a shoulder-ring at its inner end, of a boxing, a shoulder-bearing fitting around said spindle and having a portion for engagement with the boxing and a portion fitting within said shoulder-ring, means to retain the shoulder-bearing in place, the inner edge of the portion of said shoulder-bearing which extends within the shoulder-ring being cut away, 10 packing arranged within said shoulder-ring around the spindle in the recess formed by cutting away said edge and a fiber ring for retaining said packing in place.

3. The combination, with a spindle having a shoulder-ring at its inner end, of a shoulder-bearing fitting around said spindle and having a portion for engagement with the boxing and a portion fitting within said

shoulder-ring, a sleeve arranged midway between the ends of said spindle to which it is secured whereby the shoulder-bearing is retained in place, a boxing having a portion adapted to fit around the end of said spindle and an offset portion, extending over and beyond the sleeve, provided with means for engagement with the shoulder-bearing, and packing arranged around the spindle between the ends of said sleeve and the boxing and shoulder-bearing, respectively, for the purpose specified. 20 25 30

In testimony whereof I affix my signature in presence of two witnesses.

JOHN SCOTT TAYLOR.
